UNITED STATES PATENT OFFICE.

ARTHUR ISHERWOOD, OF HYDE PARK, MASSACHUSETTS, ASSIGNOR TO THOMAS KENYON, OF MANCHESTER, ENGLAND.

STRIPPING MEANS FOR MACHINES FOR STITCHING TOGETHER PIECE ENDS.

1,049,304.

Specification of Letters Patent.

Patented Dec. 31, 1912.

Application filed June 12, 1911. Serial No. 632,662.

To all whom it may concern:

Be it known that I, ARTHUR ISHERWOOD, a subject of Great Britain, residing at Hyde Park, in the county of Norfolk, State of 5 Massachusetts, have invented a certain new and useful Improvement in Stripping Means for Machines for Stitching Together Piece Ends, of which the following is a specification, reference being had therein to 10 the accompanying drawings.

The invention is applicable more especially to machines designed for stitching together piece-ends; that is to say, to machines for stitching together the final end of one 15 piece or web of cloth and the leading end of a second piece or web, and so on successively, in order that a series of pieces or webs may be joined together in a continuous 20 succession, as required in various processes of treating cloth in which the material travels lengthwise through the apparatus in which it is operated upon.

Machines at present in use for the purpose stated are provided with two series of 25 points or pins traveling side by side at a short distance apart, and passing, respectively, at opposite sides of stitching devices. Two piece-ends to be united to each other are impaled upon the said points or pins, 30 one piece above the other. By the onward movement or travel of the points or pins the two piece-ends, one thereof lying upon the other as just explained, are fed transversely to and past the stitching devices, 35 and thereby united by a line of stitches (seam) extending across the pieces at a short distance from the extremities thereof. As the stitching progresses, the projecting 40 extremities are trimmed off close alongside the line of stitches, beyond the said line, by trimming devices located beyond the stitching devices. At the delivery side of the 45 stitching devices the material is removed from the points or pins, and devices have heretofore been provided for stripping the material from the points or pins. Difficult 50y has been experienced, however, in effecting the removal or stripping of the narrow widths that are trimmed off from beyond the line of stitches. These narrow widths have a tendency to remain clinging 55 to the points or pins, particularly in the case of light-weight or coarse-mesh goods, and devices such as prior to the present invention were in general use have proved in-

efficient. In some cases, such devices have tended to become clogged with threads or portions of cloth carried to them by the points or pins, with the result that the points or pins have been broken.

The invention employs, in the combination with one or more continuous traveling series of points or pins of a machine for stitching together piece-ends, continuous stripping means traveling in unison with 60 the said series, and preferably, though not necessarily in all instances, having slots or openings through which the points or pins project to receive the piece-ends thereon, the path of the said continuous stripping 65 means diverging from that of the points or pins after passing the stitch-making point, so that the stripping means lifts the pieces of cloth from the points or pins and frees 70 them from the latter.

The invention may be embodied in different forms and constructions.

One embodiment of the invention is illustrated in the drawings, in which latter,—

Figure 1 shows in perspective certain of 80 the general features of a so-called whale-back piece-end sewing machine, with the said embodiment applied thereto. Fig. 2 shows in side elevation the parts which are shown in Fig. 1, the fixed framework being 85 represented merely in outline.

Having reference to the drawings, the fixed framework is marked 1, and at 2 are represented the stitching devices, which in practice may be of any approved character. 90 The two traveling series of points or pins upon which the piece-ends to be joined together are impaled are indicated at 3, 4, they being shown as carried, in the case of the form of machine chosen for the purpose 95 of illustrating one manner of carrying the invention into effect, by endless chains 5, see dotted lines in Fig. 2. In the upper portion of the machine, at front and rear of the stitching devices, the said chains slide 100 along fixed guideways or pathways (not necessary to be shown since they are of well-known character). The chains extend also around driving sprocket-wheels at 6, Fig. 2, and adjustable carrying bowls or 105 pulleys at 7, same figure. Traveling movement in the direction of the arrows in Figs. 1 and 2 is communicated to the chains by devices not necessary to be shown. The trimming devices, represented by a pair of 110

cutter-disks α , α , coacting with each other, are located to act upon the piece-ends at a point slightly beyond the stitching devices, *i. e.* at the left thereof in the drawings.

5 In carrying the invention into effect in connection with the old construction and arrangement which has thus far been described, I provide in connection with each traveling series of points or pins a traveling 10 stripper consisting of an endless flexible band 8 having openings or slots, as at 8^a, to receive the said points or pins. In the upper portion of the machine, in advance of the stitching devices, the stripper band occupies 15 a position at the bases of the points or pins, and the cloth-receiving portions of the points or pins project through and above the stripper-band. In traveling to and past the stitching devices and trimming devices 20 the stripper-band remains in this position at the bases of the points or pins, but at a convenient point at the delivery side of the trimming devices I mount upon a stand or bracket 9 projecting from the fixed frame 1 25 a guide-sheave or roll 10 by means of which the stripper-band is guided outward from the bases of the points or pins and entirely clear of the latter. At this place in the conjoint travel of the series of points or pins 30 and the stripper-band the latter, and with it the portions of cloth impaled upon the said points or pins, are lifted entirely above and clear of the points or pins. Thereby the said portions of cloth are effectually and 35 completely stripped from the points or pins.

After passing the guide-sheave or roll 10, the stripper-band is conducted below the lower portion of the series of points or pins and the carrying chain for such series, the 40 said stripper-band being supported and guided by means of guide-rolls 11 and 12, mounted upon stands 13, 13, carried by the fixed frame 1 at opposite ends of the latter, such guide-rolls being located properly to 45 hold the returning portion of the stripper-band entirely clear of the points or pins at the places where the said carrying chain passes around the driving sprocket-wheel 6 and the guide-bowl or pulley 7. After 50 changing their direction of movement around the carrying bowl or pulley 7 and guide-roll 12, the traveling chain and strip-

per-band converge, the pins of the traveling chain reentering the slots of the stripper-band, and the band lying close to the bases 55 of the pins throughout the upper portion of the machine.

What is claimed as the invention is,—

1. The combination with stitching devices, and a continuous traveling series of points 60 or pins on which the piece-ends to be stitched together are impaled, and by the travel of which they are fed past the stitching devices, of a continuous flexible stripper traveling in unison with the said series, the 65 paths of said series and stripper diverging after passing the stitch-making point, whereby the stripper frees the pieces of cloth from the points or pins.

2. The combination with stitching devices, 70 and a continuous traveling series of points or pins on which the piece-ends to be stitched together are impaled, and by the travel of which they are fed past the stitching devices, of a continuous flexible stripper 75 traveling in unison with the said series and having slots or openings through which the points or pins project to receive the piece-ends thereon, the paths of the said continuous stripper and of the points or pins di- 80 verging after passing the stitch-making point, so that the stripper frees the pieces of cloth from the points or pins.

3. The combination with stitching devices and trimming devices, of two continuous 85 traveling series of points or pins at opposite sides of said stitching and trimming devices, on which the piece-ends to be stitched together are impaled, and by the travel of which they are fed past the stitching and 90 trimming devices, of stripping means traveling in unison with the two series of points or pins, the paths of said series and strip- 95 ping means diverging after passing the stitch-making and trimming points, whereby the pieces of cloth are freed from the points or pins.

In testimony whereof I affix my signature in presence of two witnesses.

ARTHUR ISHERWOOD.
